(57) **CLAIM**

The ornamental design for a sputter target for a physical vapor deposition chamber, as shown and described.

DESCRIPTION

FIG. 1 is a top isometric view of a sputter target for a physical vapor deposition chamber according to our design. FIG. 2 is a top plan view thereof.

FIG. 3 is a bottom plan view thereof.

FIG. 4 is a front elevation view thereof.

FIG. 5 is a back elevation view thereof.

FIG. 6 is a left elevation view thereof.

FIG. 7 is a right elevation view thereof; and,

FIG. 8 is an enlarged cross-sectional view taken along line 8-8 in FIG. 2.

The dashed lines in FIGS. 1-8 represent unclaimed environment and form no part of the claimed design.
